United States Patent Office

Des. 187,296
Patented Feb. 23, 1960

187,296

THERMOSTAT

Salvatore Merendino and Harry R. Greene, Pasadena, Calif., assignors to General Controls Co., Glendale, Calif., a corporation of California

Application January 19, 1959, Serial No. 54,225

Term of patent 14 years

(Cl. D52—7)

FIG. 1.

FIG. 2.

FIG. 3.

FIG. 4.

FIG. 5.

FIG. 6.

Figure 1 is a view in front elevation of a thermostat embodying my new design;

Figure 2 is a view in elevation showing the rear of the same;

Figure 3 is a bottom plan view thereof;

Figure 4 is a top plan view thereof;

Figure 5 is a view in elevation of a side of the same on a reduced scale; and

Figure 6 is a perspective view of the same on a reduced scale.

The undisclosed side of the thermostat is substantially the same in appearance as the side shown.

It is understood that the full line perforations shown

are repeated throughout the area indicated in the drawing.

The essential features of the design reside in those portions shown in full lines.

We claim:

The ornamental design for a thermostat, as shown and described.
